US00D634643S

(12) **United States Design Patent**
Caldwell et al.

(10) **Patent No.:** US D634,643 S
(45) **Date of Patent:** ** Mar. 22, 2011

(54) **CONDIMENT PACKAGE**

(75) Inventors: **Craig S. Caldwell**, Slippery Rock, PA (US); **John Marshall**, Pittsburgh, PA (US); **William F. Rasile**, Allison Park, PA (US)

(73) Assignee: **H.J. Heinz Company**, Pittsburgh, PA (US)

(**) Term: **14 Years**

(21) Appl. No.: **29/360,312**

(22) Filed: **Apr. 23, 2010**

(51) **LOC (9) CL** 09-05

(52) **U.S. CL** D9/707

(58) **Field of Classification Search** ..... D9/707, D9/702-703, 761, 731, 414, 418, 710, 430-432; D7/590, 600.1; 215/328; 222/92, 105, 215, 222/145.1, 95, 183; 383/9, 22, 59-60, 901; D24/118, 207; 128/114.1, DIG. 24

(57) **CLAIM**

The ornamental design for a condiment package, as shown and described.

DESCRIPTION

FIG. 1 is a top rear perspective view of a condiment package showing a first embodiment of our new design.

FIG. 2 is a bottom rear perspective view thereof.
FIG. 3 is a top front perspective view thereof.
FIG. 4 is a bottom front perspective view thereof.
FIG. 5 is a top plan view thereof.
FIG. 6 is a bottom plan view thereof.
FIG. 7 is a side elevational view thereof, the other side being a mirror image.
FIG. 8 is a front elevational view thereof.
FIG. 9 is a rear elevational view thereof.
FIG. 10 is a top rear perspective view of a condiment package showing a second embodiment of our new design.
FIG. 11 is a bottom rear perspective view thereof.
FIG. 12 is a top front perspective view thereof.
FIG. 13 is a bottom front perspective view thereof.
FIG. 14 is a top plan view thereof.
FIG. 15 is a bottom plan view thereof.
FIG. 16 is a side elevational view thereof, the other side being a mirror image.
FIG. 17 is a front elevational view thereof.
FIG. 18 is a rear elevational view thereof.
FIG. 19 is a top rear perspective view of a condiment package showing a third embodiment of our new design.
FIG. 20 is a bottom rear perspective view thereof.
FIG. 21 is a top front perspective view thereof.
FIG. 22 is a bottom front perspective view thereof.
FIG. 23 is a top plan view thereof.
FIG. 24 is a bottom plan view thereof.
FIG. 25 is a side elevational view thereof, the other side being a mirror image.
FIG. 26 is a front elevational view thereof.
FIG. 27 is a rear elevational view thereof.
FIG. 28 is a top rear perspective view of a condiment package showing a fourth embodiment of our new design.
FIG. 29 is a bottom rear perspective view thereof.
FIG. 30 is a top front perspective view thereof.
FIG. 31 is a bottom front perspective view thereof.
FIG. 32 is a top plan view thereof.
FIG. 33 is a bottom plan view thereof.
FIG. 34 is a side elevational view thereof, the other side being a mirror image.
FIG. 35 is a front elevational view thereof; and,
FIG. 36 is a rear elevational view thereof.
The broken line showing of a graphic image on the bottom of the condiment package is for illustrational purposes only and forms no part of the claimed design.
